UNITED STATES PATENT OFFICE.

MAURICE F. GEER, OF IRONDEQUOIT, NEW YORK, ASSIGNOR TO GENERAL RAILWAY SIGNAL COMPANY, OF GATES, NEW YORK, A CORPORATION OF NEW YORK.

AUXILIARY TIME-KEY FOR SELECTIVE RAILWAY SIGNALING SYSTEMS.

1,291,473.

Specification of Letters Patent.

Patented Jan. 14, 1919.

Application filed July 23, 1915. Serial No. 41,527.

To all whom it may concern:

Be it known that I, MAURICE F. GEER, a citizen of the United States, and a resident of the town of Irondequoit, in the county of 5 Monroe and State of New York, have invented a new and useful Auxiliary Time-Key for Selective Railway Signaling Systems, of which the following is a specification.

10 This invention has for its more special object to improve the construction of the selective signaling calling key, shown, described and claimed in United States Patent No. 1,105,766, granted to M. F. Geer and 15 R. C. Leake on August 4th, 1914, in manner permitting its use as an auxiliary time key at a central station for sending over the telephone line of a selective railway signaling system electric impulses corresponding 20 to the telegraphically received standard time impulses for announcing correct standard time daily at every substation of the railway line. As by this invention this service is assured by use of a single time key the invention also is an improvement upon the 25 time announcing system or devices described and claimed in United States Patent No. 1,121,823, granted to M. F. Geer, on December 22nd, 1914, which shows a manually 30 operative switch for closing motor-generator circuits, a manually operative time key providing only for sending over the selective signaling telephone line certain negative impulses corresponding to the received telegraphic time impulses, and a push button 35 device assuring circuits giving final necessary positive impulses which restore all time indicating substation selector devices to normal condition for resuming selective signaling. The present invention thus includes a 40 novel construction of one time key device operatively combining all three last above-named functions, and not requiring watchful attention of the operator or train despatcher at the central station.

45 Other objects and advantages will appear as the description of the invention progresses, and the novel features of the invention will be particularly pointed out in the 50 appended claims.

Reference is made to the accompanying drawings forming part of this specification, and in which:

55 Figure 1 is a plan view of the improved time key with a few front parts broken

away; Fig. 2 is a front view of the complete key; Fig. 3 is a side elevation of the key; Fig. 4 is a fragmentary front vertical section on the line *a*—*a* in Fig. 3; Fig. 5 is a detail vertical section on the irregular line 60 *b*—*b* in Fig. 4; Fig. 6 is a diagram indicating the electric circuits involved in the operation of apparatus at a central station or train despatcher's office and including the time key, one of a group of calling keys used 65 in selective railway signaling, a motor generator, a line relay and the incoming time wires; there also being indicated the telephone line wires and two selector devices in circuit therewith at two sub-stations; each 70 selector having a bell announcing a call from the central station and also the time indications transmitted therefrom. Figs. 1 to 5 are drawn about twice normal size.

The time key frame comprises a front 75 plate 1, a back plate 2, and interposed spacing bars all suitably fastened together. By and between the frame plates 1, 2, is sustained a gear train 3, and a coiled spring 4, connected to a shaft 5, which is extended forward and fixedly carries the finger-hold or head 7, by which the time key is primarily actuated. A lower gear train shaft 8 preferably carries the movable parts of a centrifugal brake or speed governor device 9, 85 located at the rear face of the frame. An intermediate shaft 10, of the gear train fixedly carries a locking wheel 11, having a part adapted for engagement by a suitable latch device to lock the gear train at rest 90 after the wheel 11 has made a partial clockwise revolution. This latch device may be the illustrated arm 12, carrying a fixed pin 13, adapted to enter a hole 14, in the wheel 11, and fixed to a rod 15 having a head or 95 push-button 16 and movable endwise in the frame plates 1, 2. The pin 13 has one sliding bearing in the frame plate 2, and is normally pressed to the face of the gear wheel 11, and into its alined hole 14 by a 100 suitable spring 17, forked at one end around the pin 13, and bearing on a collar, 18, fixed to said pin, the other end of the spring being fixed to the rear frame plate 2. The shaft 5, having the head 7, fixedly carries a segmental contact 19, and also has a fixed radial stop pin 20 adapted to coact with a radial stop pin 21 fixed to the gear train shaft 10, carrying the stop wheel 11. The shaft 10 also fixedly carries three succes- 105 110

sively operating contacts 22, 23, 24, the ones 22, 24, lying rotatively in the same plane and therefore adapted to coact with the same resilient contact 25 held to an insulating block 26, fastened to the front frame plate 1. The second acting contact 23 is adapted to engage another resilient contact 27, fixed to the block 26, which also fixedly carries a third resilient contact 28, adapted for engagement by the above named segmental contact 19, on the shaft 5. The first operative contact 22 is shown having two teeth, the first slightly longer at its acting end or face than the other, and the next operative segmental contact 23 has a still longer acting face and the segmental acting face of the last operative contact 24 is longer than that of the contact 23, whereby the frequency and duration of certain hereinafter named electric circuits is regulated or controlled.

In the diagram of Fig. 6, the letter A generally indicates the herein-described improved time key, the letter B generally indicates one of a group of calling keys used at a central station in electric railway signaling, and such as is shown, described and claimed in United States Patent No. 1,105,766, granted to M. F. Geer and R. C. Leake on August 4th, 1914. C indicates a battery, and D indicates an electromagnet which may close a circuit through the battery which starts a motor generator indicated at E. F. G indicates a pole-changing line relay. H, I, indicate two telephone line wires with which are shown connected two selector devices J, K, at two respective sub-stations, each selector having a responsive call and time bell L, said selector being of the general type shown, described and claimed in United States Patent No. 1,118,120, granted to M. F. Geer and R. C. Leake, on November 24th, 1914. M indicates an electromagnet energized from the incoming time wires N, O. All parts indicated at A, B, C, D, E, F, G, M, N, O, are arranged at the central station, and the selector devices, such as J, K, are arranged one at each sub-station of a railway where correct standard time is to be indicated daily under control of the operator's time key A, at the central station. The circuits involved in operating the time key and directly associated apparatus are as follows:

The first circuit is from positive battery C, by wires 30, 31, 32, to engaged contacts 19, 28, wires 33, 34, coil 35 of magnet D, and wires 36, 37, 38, to negative battery.

The second circuit is from positive battery by wires 30, 31, 39, brush 40, of motor E, and through its armature to brush 41, and wire 42, to point 43, and a branch circuit flows from wire 39, through wires 44, 45, motor field coil 46, wire 47, to wire 42, and another branch circuit flows from the junction of wires 44, 45, through wire 48, fixed

resistance 49, wire 50, to adjustable switch 51, cutting in more or less of a variable resistance 52, which connects with point 43, whence the current flows through wire 53, and engaged contact and armature 54, 55, 70 and wires 37, 38, to negative battery.

The third circuit is from positive battery by wires 30, 31, 32, 56, to engaged contacts 22, 25, to diagrammatic conductor 57, and wires 58, 59, to coil 60, of positive magnet 75 pole 61, of relay G, and thence by wires 62, 63, 38, to negative battery.

The fourth circuit is from brush 64, of generator F, its armature and brush 65, wire 66, a pivoted contact arm 67, movable by the head 68, of the relay armature 69, which simultaneously moves another pivoted contact arm 70. When this armature is attracted by energized positive magnet pole 61, to make the fourth circuit, the arms 67, 70, are respectively engaged with contacts 71, 72, and the fourth circuit thus is by wire 66, to arm 67, contact 71, and wire 73 to line wire H, and thence by wires 74, to and through the positive magnet coils of all the selector devices such as J, K, at all sub-stations and thence by wires 75, to the other line wire I, and by contact 72, arm 70, wire 76, generator field coil 77, and wire 78, to generator brush 64.

The fifth circuit is from positive battery by wires 30, 31, 32, 56, engaged contacts 23, 27, wire 79, contact 80, attracted time-wire magnet armature 81, wires 82, 83, to the coil 84, of negative magnet pole 85, of relay G, 100 to wire 86, and wires 63, 38, to negative battery.

The sixth circuit is from brush 64, of generator F, its armature and brush 65, wire 66, pivoted contact arm 67, which now is 105 moved by energized negative relay pole 85 and armature 69, to a contact 88, on line wire I, while the contact arm 70, now engages a contact 89, on line wire H, and the sixth circuit thus is by wire 66, to arm 67, 110 and contact 88, to line wire I, and thence by wires 75, to and through the negative magnet coils of all the selector devices such as J, K, and thence by wires 74, to the other line wire H, to contact 89, arm 70, wire 76, 115 generator field coil 77, and wire 78, to generator brush 64.

The seventh circuit is from positive battery by wires 30, 31, 32, 56, to engaged contacts 24, 25, and thence through wires 58, 120 59, to coil 60, of positive magnet pole 61, of relay G and by wires 62, 63, 38, to negative battery.

The eighth circuit is a final time key circuit necessarily following the shifting of relay armature 69, by the prior made seventh circuit, and is similar to the above named fourth circuit made through the generator F and the positive coil 60, of the relay G.

In the diagram of Fig. 6 a spiral spring 130

90, on the push rod 15, is substituted for the plate spring 17, shown in Figs. 3, 4 and 5, of the drawings, and a weight 91, hung from the shaft 5, is substituted for the spring 4, of Figs. 1 and 3, for rotating the shaft 5, counter-clockwise, and suitable condensers 92, and impedances 93, are introduced between and in the line wires H, I.

The general operation of coacting parts of 10 the time key A, is as follows: The attendant or train despatcher at the central station turns the button 7 clockwise from the normal resting position shown in Figs. 2, 3 and 6, for about ninety degrees, thereby likewise 15 turning shaft 5, until its pin 20, strikes a stop pin 94, in the frame plate 1. This shaft movement first engages the segmental contact 19, on shaft 5, with the fixed contact 28, and the respective contacts 22, 23, 24, on 20 shaft 10, subsequently successively engage their respective fixed contacts 25, 27, as shaft 10 is being rotated clockwise one full revolution by the gear train 3, after the attendant releases the button 7, and while this button 25 and the shaft 5 and contact 19 are being turned counter-clockwise by the spring 4, said counter-clockwise movement of shaft 5, and clockwise movement of shaft 10, and its contacts 22, 23, 24, temporarily stopping 30 when the latch pin 13, enters the approaching hole 14, in the clockwise turning train gear wheel 11, and thus locks the gear train at which time the second acting contact 23 still engages the contact 27. When the push 35 button 16, later is manually pressed inward the shaft 15, and arm 12, withdraw the pin 13, from the hole 14, of gear 11, thus allowing further and final short counter-clockwise movement of shaft 5, which disengages the 40 segmental contact 10 from spring contact 28; and also allowing further and final clockwise movement of shaft 10, which engages the contacts 24, 25, and causes the pin 21, of shaft 10, to stop against the end of the pin 45 20, of shaft 5, and all coacting parts again have assumed normal inoperative positions shown in Fig. 2 of the drawings.

The operation of the time key with more special reference to the electric circuits is as 50 follows: From two to five minutes before the known time at which the telegraphic time indicating impulses begin to arrive at the central station over the wires N, O, the attendant or train despatcher gives the button 7 55 and shaft 5 a quarter turn clockwise and need not give further watchful attention to assure automatic and correct announcement of true standard time at every sub-station. Almost immediately after beginning this 60 clockwise turning of shaft 5, its segmental contact 19, rides against and under the contact 28, thereby making the first hereinabove named circuit through the magnet D, and attracting armature 55, to contact 54, thereby 65 making the second hereinabove named cir-

cuit which starts the motor generator E, F, some little time before the two teeth 22, on the shaft 10, now rotating clockwise, successively engage the contact 25, to twice close the third hereinabove named circuit. The 70 delay in closing this third circuit after starting of the motor-generator by the second circuit provides for generation of sufficient energy to assure that when the third circuit is twice closed and the positive pole 61 of relay 75 G, is thereby twice energized and attracts the armature 69, thereby twice making the hereinabove named fourth circuit, the current flowing from the generator F, in said fourth circuit will be amply strong to actuate the 80 selectors such as J, K, at all the sub-stations. The fourth circuit when thus twice made through the initiative of the two teeth on contact 22, sends two corresponding positive electric impulses through the line wire H, 85 and wires 74, to twice actuate or pick up the positive sectors of all the selectors, as J, K, thereby certainly adjusting the selectors to assure later operation of their negative sectors one tooth or stop for each electric impulse sent into the central station through the time wires N, O. The impulses sent out over the line wire H, and through the selectors J, K, by the fourth circuit return by the line wire I, to the motor generator E, F. 90 Immediately the second and last tooth 22, leaves the contact 25, the segmental contact 23, engages the contact 27, thereby intermittently making the hereinabove named fifth 95 circuit as often as the armature 81, is attracted by the magnet M, when it is energized by impulses sent over the time wires N, O. Each closing of said fifth circuit energizes the negative magnet pole 85, of relay G, thereby attracting its armature 69, and sending by the now made hereinabove named sixth circuit a corresponding negative impulse over the line wire I, and through wires 75, 74, to pick up the negative sectors of all 100 the selectors, as J, K, one tooth or stop for each time wire impulse until the last tooth is advanced by the pawl coupled to the selector armature, and all later negative time wire impulses will simply move this pawl without 105 advancing the sector. All impulses sent over the line wire I, through the selectors J, K, by the sixth circuit return by the line wire H, to the motor generator E, F. After the shaft 5, had been turned clockwise one-quarter 110 around and the shaft head 7, then is released by the attendant, and during the counter-clockwise return movement of the shaft by the spring 4, the contacts 19, 28, remain engaged thereby maintaining the second motor generator circuit for sending either positive 115 or negative impulses over the line wires H, I, and correspondingly actuating the selectors J, K, as above described.

Almost immediately after the contacts 23, 27, are engaged to make the fifth circuit the 120 125 130

latch pin 13, automatically enters the hole 14, of train gear 11, thereby locking the gear train 3, thus stopping the counter-clockwise turning of shaft 5, and the clockwise turning 5 of shaft 10 and its three contacts when the contact 27 rests upon a central or intermediate portion of the segmental contact 23, to thereby certainly maintain the fifth circuit during sending of any required number of 10 negative impulses by the sixth circuit through the selectors J, K. As each time wire impulse is negatively sent over the telephone line I, H, to actuate the negative sectors of the selectors, other circuits through the generator, the 15 wires H, I, and two finally engaged contacts located in the selector casing are closed through the wires 1, 1¹, to sound the bell once for each time wire impulse. These momentary impulses begin about two minutes before 20 the hour at which standard time is telegraphically received, say at 11 o'clock a. m., and the impulses succeed each other at one second intervals until fifteen seconds before 11, when they cease until exactly 11 o'clock, 25 when one impulse is received which indicates the exact hour of 11 a. m., which thus will be indicated or announced by one easily distinguishable stroke of the bell L, at each and every sub-station along a railway line. 30 It also is customary to send time impulses each second for two minutes after the exact hour.

After completion of the time announcements at all sub-stations the attendant at 35 the central station may at his early convenience restore all parts of all sub-station selectors to normal operative positions for resuming selective railway signaling through the respective calling keys B. This the attendant accomplishes by simply pressing the button head 16 of shaft 15, thereby withdrawing the latch pin 13, from hole 14, of 40 wheel 11, which unlocks the gear train 3, and allows the spring 4 to resume counter-clockwise rotation of shaft 5, and clockwise rotation of the contact carrying shaft 10. The first effect is to disengage the now turning contact 23 from contact 27, thereby 45 breaking the fifth circuit made through the coil 84, of the negative magnet pole 85, of relay G, and thus also making it impossible to disturb later operation of the selective signaling system by any impulses which may mistakenly be sent over the time wires 50 N, O. Immediately after breaking of the fifth circuit by disengagement of contacts, 23, 27, the contacts 24, 25, are engaged thereby making the hereinabove named seventh circuit through the positive relay coil 55 60, and attracting armature 69, to move its head 68, to the left and thus make the hereinabove named final eight time key circuit by which one necessary final positive impulse is sent over the line wires H, I, to and 65 through all sub-station selectors, as J, K,

and when this eighth circuit is broken by disengagement of contacts 24, 25, the coacting parts of the selectors at all sub-stations automatically back gravitally to normal positions in readiness for operation of the selective railway signaling system over the telephone line wires H, I. The first circuit is last broken by disengagement of the contacts 19, 28, just prior to the engagement of stop pins 20, 21, as the time key parts resume 70 normal inoperative positions shown in Fig. 2, of the drawings.

The operation of coacting parts of the selectors is more fully explained in the aforesaid Patent No. 1,118,120; and the operation of selectors relatively to a time announcing system is shown, described and claimed in the aforesaid United States Patent No. 1,121,823; and the operation of an individual calling key relatively to selectors 80 in a selective signaling system is shown, described and claimed in the aforesaid United States Patent No. 1,105,766.

A quite brief reference to the circuits involved when one of the calling keys B, is 90 operated at the central station, will now be made in order to more clearly explain the interrelations of the selective railway signaling and time announcing systems. The calling key B, has one shaft 94, carrying a segmental contact 95, adapted to a line wire contact 96. Another shaft 97, fixedly carries three contacts 98, 99, 100, respectively adapted to line wire contacts 101, 102, 103. Aside from the fact that the contact 99, carries 100 three teeth instead of one segmental contact face, the respective parts 94, 95, 96, 97, 98, 99, of the calling key B, are substantial duplicates of the parts 5, 19, 28, 22, 23, 24, of the above described time key A, and operate in substantially similar manner but with partly different electric circuits, as follows: As contacts 95, 96, engage there is formed a ninth circuit from positive battery C, through wires 30, 104, 105, 106, contacts 95, 96, wires 107, 34, magnet coil 35 and wires 36, 37, 38, to negative battery. The closing of this circuit attracts armature 55, thereby making a tenth circuit which is similar to the above described second circuit and starts the motor generator E, F, and shortly after this tenth circuit is made, the two teeth 98, engage contact 101, thereby twice 110 making an eleventh circuit which flows from positive battery by wires 30, 104, 105, 107, 120 contacts 98, 101, wires 108, 109, and thence as in the fourth circuit by wires 59, relay magnet coil 60, and wires 62, 63, 38, to negative battery. Making this eleventh circuit caused relay magnet pole 61, to attract 125 armature 69, thereby twice making a twelfth circuit through generator E, similar to the above named fourth circuit, and sending two positive impulses by the telephone wires H, I, to each of the selectors, as J, K, of the 130

signaling system for twice picking up their positive sectors. After the contacts 98, 101, are disengaged the three teeth of contact 99 successively engage the contact 102, thus 5 thrice making a thirteenth circuit flowing from positive battery by wires 30, 104, 105, 110, contacts 99, 102, wire 111, and thence as in the above named fifth circuit by wire 83, relay magnet coil 84, and wires 86, 63, 10 38, to negative battery. Making this thirteenth circuit caused relay magnet pole 85, to attract armature 69, thereby thrice making a fourteenth circuit through the generator F, similar to the above named sixth circuit, and sending three negative impulses by 15 the telephone wires I, H, to each of the selectors, as J, K, for thrice picking up their negative sectors. After the contacts 99, 102, are disengaged the segmental contact 100 20 engages the contact 103, thereby making a fifteenth circuit from positive battery through wires 30, 104, 112, contacts 100, 103, wire 113, wire 109, and thence as in the above named seventh circuit through wire 25 59, coil 60, of positive magnet pole 61, of relay G, and by wires 62, 63, 38, to negative battery. The sixteenth circuit is a final calling key circuit necessarily following the shifting of relay armature 69, by the prior 30 35 made fifteenth circuit, and is similar to the above named fourth and twelfth circuits, and sends a single positive impulse by the wires H, I, to each of the selectors, as J, K, of the signaling system for once and finally picking up their positive sectors.

As the first calling key contact 98, has two teeth and its second contact 99, has three teeth, the calling key will cause transmission of first two positive and then three negative 40 impulses over the telephone line which sets the respective positive and negative selector arms properly in line at the one particular sub-station whose selector responds to a "two-three" impulse code, and the last positive 45 impulse imparted by engagement of the contacts 100, 103, will therefore cause the selector plunger to close the contacts at that particular sub-station and establish circuits necessary for thereat operating the signal 50 55 or switch or other devices. After breaking of the final sixteenth circuit by automatic separation of the contacts 100, 103, the parts of all the selectors of the signaling system are automatically returned by gravity to initial operative positions ready for the next call of the train despatcher at the central station. It will be remembered that when the train despatcher uses one of the calling 60 65 keys B adapted to communicate only with one particular sub-station, the bell L, at that sub-station will alone be sounded, but when the time key A, is used the bells L at all the sub-stations will be sounded simultaneously to responsively indicate by corresponding electric impulses sent over the telephone line

the standard time impulses received at the central station over the telegraph line.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention. 70 75

What I claim as new and desire to secure by Letters Patent of the United States, is:

1. In a combined time announcing system and selective signaling system, in combination: a pair of line wires; a plurality of selectors connected across said line wires; a time signal controlled by each selector; a time calling key comprising a manually movable member; means for returning said member from its operated position to its normal position; circuit closing means operated by said member during the first part of its return movement for sending impulses of one polarity over said line wires; a time circuit for sending impulses of an opposite polarity over said line wires; other circuit closing means operated by said member and closed in an intermediate position of the return movement of said member for automatically connecting said time circuit to said line wires; means for holding said member in said intermediate position and said other circuit closing means in its closed position; manually operable means for releasing said last mentioned means; and a third circuit closing means operated by said member during the final part of its return movement for sending an impulse over said line wires of the same polarity as sent by said first mentioned circuit closing means. 100 105

2. In an individual calling key, in combination: a manually movable member; means for returning said member to its normal position after having been moved manually; circuit closing means operated by said member; a pair of line wires; a circuit automatically connected to said line wires by said circuit closing means; means for arresting the movement of said member in a circuit closing position; means for releasing said member; and other circuit closing means closed by the operation of said member after it has been released. 110 115

3. In an individual calling key, in combination: a manually movable member; means for returning said member from its operated position to its normal position; circuit closing means operated by said member for sending impulses of one polarity; a normally open time controlled circuit for sending impulses of an opposite polarity; means operated by said member at an intermediate point in its return movement for automatically closing said circuit; and manually re- 120 125 130

leasable means for arresting the movement of said member at said intermediate point in its return movement.

4. In an individual calling key, in combination: a manually operated member; means for returning said member to its normal position after having been operated normally; a pair of line wires; circuit closing means operated by said member; other circuit closing means closed in an operated position of said member; means for locking said member in an operated position and for holding said last mentioned circuit closing means, closed; a time circuit automatically connected to said line wires by said other circuit closing means; means for releasing said member; and a third circuit closing means operated by said member when it is released.
- 10 5. In an individual calling key, in combination: a manually movable member; means for returning said member from its operated position to its normal position; a gear wheel operated by said member; a circuit closing means operatively connected to said gear for sending electrical impulses in one direction; a circuit for sending impulses in an opposite direction; a second circuit closing means operatively connected to said gear for automatically closing said circuit; a detent coacting with said gear for arresting the movement of said member and for holding said second circuit closing means in its closed condition; means for releasing said member; and a third circuit closing means operatively connected to said gear for sending a final impulse in the same direction as said first mentioned circuit closing means.
- 20 6. In a combined time announcing and selective signaling system, the combination with a line circuit of a selective signaling system, of a time circuit adapted to control current impulses in the line circuit and normally disconnected from the line circuit to permit use of the line circuit without interference, a calling key, and means operated automatically by the calling key for establishing operative connection between said time circuit and said line circuit.
- 30 7. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 40 8. In a combined time announcing and selective signaling system, the combination with a line circuit, of a time circuit adapted to control current impulses in the line circuit.
- 50 9. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 60 10. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 70 11. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 80 12. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 90 13. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 100 14. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 110 15. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 120 16. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.
- 130 17. In a combined time announcing and selective signaling system, the combination with a line circuit, of a time circuit adapted to control current impulses in the line circuit, a calling key, a motor-generator for providing electrical energy for the current impulses in the line circuit, and means operated automatically by the calling key for setting said motor-generator into operation and for establishing an operative connection between said time circuit and said line circuit.

cuit of a predetermined polarity, a calling key, circuit controlling means operated by the calling key for establishing an operative connection between said time circuit and line circuit during the first part of its movement 70 and for subsequently causing current impulses in the line circuit of opposite polarity to the impulses controlled by the time circuit during the later part of the movement of said key, and manually releasable means 75 for automatically stopping the calling key after the first part of its movement.

9. In a combined time announcing and selective signaling system, the combination with a line circuit, of selectors connected to 80 said line circuit and adapted to be stepped up and restored by characteristic impulses sent over the line circuit, a time circuit for causing impulses in the line circuit suitable for stepping up the selectors, means for 85 causing an impulse in the line circuit suitable for restoring the selectors, a calling key for automatically rendering said time circuit and said means successively effective during different ranges of movement of said 90 calling key, and manually operable means for controlling the range of movement of said calling key.

10. In a combined time announcing and selective signaling system, the combination 95 with a line circuit, of selectors connected to the line circuit and adapted to respond to the polarity and number of impulses sent over the line circuit, said selectors being conditioned by an impulse of one particular 100 polarity to be stepped up by impulses of opposite polarity and being restored by an impulse of the particular polarity, a time circuit adapted to control the sending of impulses of said opposite polarity over the 105 line circuit, a manually operable calling key, manually releasable means for stopping the calling key at an intermediate point in its movement, circuit controlling means operated by the calling key during the first part 110 of its movement for rendering the time circuit effective to send its current impulses over the line circuit, and other circuit controlling means operated by the calling key during the last part of its movement for 115 sending an impulse of the particular polarity over the line circuit.

11. In a combined time announcing and selecting signaling system, the combination with a line circuit, of selectors connected to 120 the line circuit and adapted to respond to the polarity and number of current impulses sent over the line circuit, said selectors being conditioned by an impulse of one particular polarity to be stepped up by impulses of opposite polarity and being restored by an impulse of the particular polarity, normally inactive means for supplying electrical energy to the line circuit, a relay for controlling the polarity of the electrical 125

connection between said means and the line circuit, a time circuit adapted to be connected to the relay and cause impulses of said opposite polarity to be sent over the line circuit, a calling key, means operated by the calling key for operating said normally inactive means during the movement of said key, manually releasable means for stopping the calling key at an intermediate point in

its movement, circuit controlling means 10 operated by the calling key during the first part of its movement for connecting the time circuit to said relay, and other circuit controlling means operated by the calling key during the last part of its movement for 15 controlling said relay to send impulses of said particular polarity over the line circuit.
